SOMA HERZOG OF NEW YORK, N. Y., ASSIGNOR TO NU-FASTENER CO., INC. OF NEW YORK, N. Y., A CORPORATION OF NEW YORK.

SNAP-BUTTON.

1,195,678.

Specification of Letters Patent. Patented Aug. 22, 1916.

Application filed April 11, 1916. Serial No. 90,315.

To all whom it may concern:

Be it known that I, SOMA HERZOG, a citizen of the United States, and a resident of New York city, in the county and State of New York, have invented certain new and useful Improvements in Snap-Buttons, of which the following is a specification.

This invention relates to a snap button of novel construction which may be readily manipulated and will adapt itself to any small variations in the size of its male member.

In the accompanying drawings: Figure 1 is a longitudinal section on line 1—1 Fig. 2, of a snap button embodying my invention; Fig. 2 a cross section on line 2—2 Fig. 1, and Fig. 3 a front elevation.

The male member of the fastener comprises a plate 1 provided with a rounded head 2 as usual, and does not form part of the present invention.

The female member is composed of a circular casing 3 having a peripheral flange 4, a plurality of thread holes 5, and a central opening 6, adapted for the reception of head 2. Within casing 3 there is housed a continuous resilient wire 7 bent into stellated form, the drawing showing it to be provided with four points, three of which are closed. The tips 8 of these closed points bear against flange 4, while the inner ends of the points are joined at obtuse angles, to form angular reentrant projections 9, which extend inwardly a distance beyond the edge of opening 6 so as to be accessible to head 2. The two ends of the wire 7 are disconnected and converge toward each other to form the

fourth point of the star, such ends contacting some distance from flange 4 as at 10. From this point 10 on, the wire ends are deflected laterally to diverge from each other 40 and form a pair of toes 11 that approach flange 4 on opposed curves. The result of this construction is that when the button is closed, head 2 will spread toes 11 and cause them to travel along rim 4 for such a distance as will suffice to permit a ready engagement of the head with the wire. In this way, the button may be closed with a comparatively slight pressure, and will effect a proper coöperation of the parts, even in case 50 the head has become flattened or enlarged by use. After the head has cleared the wire, the pressure on the latter will cease, so that the toes will again approach each other and the projections 9 will obtain a firm grasp 55 upon the shank of the button.

I claim:

In a snap button, a female member comprising a flanged casing, an inclosed star-shaped resilient wire having a plurality of inwardly directed angular projections adapted to engage a button shank, the two end portions of the wire that form one of the star-points being disconnected from each other at the tip of said point, said end portions first converging into operative engagement with each other at a distance from said tip, and thence diverging at said tip to form a pair of outwardly directed toes that are adapted to travel along the casing- 65 flange.

SOMA HERZOG.
